UNITED STATES PATENT OFFICE.

FRANCIS W. BELKNAP, OF FLUSHING, NEW YORK.

PORTABLE PLATFORM AND THE LIKE.

Application filed April 18, 1923. Serial No. 633,036.

To all whom it may concern:

Be it known that I, FRANCIS W. BELKNAP, a citizen of the United States, residing at Flushing, in the county of Queens and State 5 of New York, have invented certain new and useful Improvements in Portable Platforms and the like, of which the following is a full, clear, and exact description.

In construction work over bodies of water 10 subject to waves, it is very difficult to work from floating platforms for various reasons, such as because of the motion of the platform by the waves and the drift thereof with the waves. Where platforms 15 have been supported by posts upon the ground beneath the body of water, the moving of the platform to different working locations has been slow and expensive.

An object of this invention is to provide 20 an improved platform, derrick or the like for use over bodies of water, which may be supported firmly and in a level position upon the ground beneath the water, even though the ground surface may be uneven, which 25 will offer little or no resistance to waves striking the same, which may be rapidly and inexpensively shifted into different working locations, and which is relatively simple and inexpensive in construction.

Other objects and advantages will be apparent from the following description of an embodiment of the invention, and the novel features will be particularly pointed out 30 hereinafter in claim.

35 In the accompanying drawing:

Fig. 1 is a front elevation of a platform device constructed in accordance with the invention;

Fig. 2 is a sectional plan of the same, 40 taken substantially along the line 2—2 of Figure 1;

Fig. 3 is a fragmentary plan of the same taken substantially along the line 3—3 of Figure 1, with one of the buoyant devices 45 attached thereto;

Fig. 4 is an end elevation of the same with the buoyant devices attached thereto;

Fig. 5 is an elevation of a portion of a tank which may be utilized as one of the 50 buoyant devices; and

Fig. 6 is a fragmentary section through the tank, taken substantially along the line 6—6 of Figure 5.

In the illustrated embodiment of the invention, a working platform structure 1 is provided upon the upper face of a suitable

frame 2 which may be reinforced in any suitable manner such as by structural bracing 3. The frame, at each corner, is provided with vertically extending guideways 4, in each of which is vertically slidable a supporting post 5. The posts 5 are slidable in the frame independently of one another.

A pulley block 6 is secured to the platform structure of the frame adjacent each post 5, and another pulley block 7 is secured to each post adjacent the upper end thereof. A cable 8 is secured to the pulley block 7, extends around a pulley of the block 6, then over a pulley of the block 7, then 70 around another pulley of the block 6, then around another pulley of the block 7, then downwardly toward the platform and around the drum 9 of a suitable winch 10 which is mounted upon the frame or platform adjacent each post. When the winch is operated, the block and tackle device, which is provided by the cable 8 and the pulley blocks 6 and 7, will be operated thereby so that when the cable is wound upon the winch drum the platform and frame 75 will be elevated relatively to the posts 5, and when the cable is unwound from the drum of each winch the frame and platform will be lowered upon the posts. Because of the 80 separate elevating and lowering device between each post and the platform or frame, the lower ends of the posts may rest firmly upon uneven ground beneath the body of water over which the frame is disposed, 85 with the frame and platform in a level position in each new working location in which the device may be placed. Each post may be adjusted vertically from time to time, to take care of unequal settlement of the posts. 90

A pair of buoyant devices which may be closed tanks, are provided upon their periphery with eyes 12, by means of which they may be attached in any suitable manner to anchoring elements 13 that are provided for 100 this purpose adjacent to or upon the lower edge of the frame, so that when the frame is lowered from the posts the tanks will floatingly support it by reason of their buoyancy. The posts may then be individually drawn upwardly in any suitable manner, such as by cables 14, so as to be removed entirely from contact with the ground beneath the body of water, and in this condition the frame may be floated into a new 105 working location. In the new location, the posts will be allowed to drop into contact 110

with the ground beneath the body of water, and the winches will be operated to elevate the frame usually entirely above the highest water level or waves likely to be encountered 5 until it is entirely supported from the posts in a level position.

The tanks may, if desired, be allowed to remain attached to the frame, or may be collapsible so that when not in use they will 10 offer little resistance to heavy seas or wind, but to avoid the buffeting action of waves thereon, it is preferable to detach the tanks or buoyant devices from the frame and remove them to a suitable place for safe keeping 15 until it is desired to move the platform or derrick to a new working location. The framework is preferably open on all of its sides, except for the bracing, so as to allow the passage through the same of any unusually 20 high waves which may strike it, and with such a construction the frame will offer little or no resistance to the waves and wind, and the platform will remain in a substantially firm and stable position.

25 In the use of the platform or derrick it is assembled in the manner illustrated, and with the tanks attached thereto it may be floated into a working location and the frame elevated upon the posts 5 until it is 30 entirely supported by the posts. The tanks may then be detached and stored in a safe place until the platform or derrick is to be moved to a new location. When it is to be moved the tanks are reattached to the frame, 35 as indicated in Figures 3 and 4, and the winches are operated to lower the frame until the tanks support the frame entirely by their buoyancy. The cables 14 may then be pulled to elevate the posts out of contact 40 with the ground, and the platform or derrick may then be towed or floated to a new working location. In this new location the winches are operated to elevate the frame upon the posts until the frame is entirely 45 supported by the posts, after which the

tanks may again be removed and stored until the platform or derrick is to be again moved.

It will be obvious that with a platform or derrick constructed in accordance with this 50 invention, any suitable working mechanism, such as booms, pile driving mechanism or any other suitable apparatus, may be carried by the platform. While in a working position the platform will be firmly supported so that its action will be substantially 55 unaffected by any waves. When it is to be moved to a new location, it may be quickly and inexpensively floated into the new working position and reestablished in a firm position. The device is exceptionally simple 60 and inexpensive in construction. It will be obvious that various changes in the details and arrangements of parts, herein described and illustrated for the purpose of explaining the nature of the invention, may be made by those skilled in the art within the principle and scope of the invention as expressed in the appended claim.

I claim:

In portable platforms, derricks, and the like, for use over bodies of water, a frame, a plurality of supporting posts movable vertically relatively to the frame, and means acting between the frame and posts for elevating or lowering the frame relatively to the posts, and buoyant devices detachably connected to the frame upon the outer faces of said frame for supporting it by floatation when said frame is lowered relatively to the 70 posts, whereby the entire device may be floated to a new working position and the frame elevated relatively to the posts until it is supported entirely by the posts, the buoyant devices being removable to lessen 75 wave action upon the frame when the latter rests upon the posts.

In witness whereof, I hereunto subscribe my signature.

FRANCIS W. BELKNAP.
